FLASHLIGHT

Kenneth Z. Crawford, Crawfordsville, Ind.

Application August 9, 1954, Serial No. 31,775

Term of patent 7 years

(Cl. D48—24)

Fig. 1.

Fig. 2.

Fig. 3.

Fig. 4.

To all whom it may concern:

Be it known that I, Kenneth Z. Crawford, a citizen of the United States, residing at Crawfordsville, county of Montgomery, State of Indiana, have invented a new, original, and ornamental Design for a Flashlight, of which the following is a specification, reference being had to the accompanying drawing, forming a part hereof.

Fig. 1 is a front elevation of a flashlight embodying my new design;

Fig. 2 is a rear elevation of the flashlight;

Fig. 3 is a top plan view; and

Fig. 4 is a side elevation.

I claim:

The ornamental design for a flashlight, as shown.
